[57] CLAIM

The ornamental design for a container attachment, as shown and described.

DESCRIPTION

FIG. 1 is a perspective view of a container attachment showing my new design;

FIG. 2 is a front elevation view thereof;

FIG. 3 is a rear elevation view thereof;

FIG. 4 is a side elevation view thereof; and,

FIG. 5 is a perspective elevation view thereof.

FIGS. 2-5 are shown exploded for ease of illustration. The broken line showing of the container in FIG. 1 is for illustrative purposes only and forms no part of the claimed design.
